UNITED STATES PATENT OFFICE.

JOHN WILLIAM SCHAEFER, OF BEARDSTOWN, ILLINOIS.

STORE-WINDOW DISPLAY-MACHINE.

1,108,008.

Specification of Letters Patent. Patented Aug. 18, 1914.

Application filed November 14, 1913. Serial No. 801,049.

To all whom it may concern:

Be it known that I, JOHN W. SCHAEFER, a citizen of the United States, residing at Beardstown, in the county of Cass and State 5 of Illinois, have invented a new and useful Store-Window Display-Machine, of which the following is a specification.

The primary object of this invention is to provide a window display or rack, so constructed as to be capable of supporting merchandise of all descriptions and keeping same continually in motion.

Another and more specific object of the invention is to provide a window display machine having a plurality of oscillating arms and platforms to support merchandise, which are actuated by a crank shaft and suitable connecting rods and links.

With these and other objects in view as 20 will become more apparent as the description proceeds, the invention consists in certain novel features of construction, combination and arrangement of parts as will be hereinafter more fully described and 25 claimed.

For a complete understanding of my invention, reference is to be had to the following description and accompanying drawings, in which—

30 Figure 1 is a rear elevation of my display machine, Fig. 2 is a vertical section taken on the plane of line 2—2 of Fig. 1, Fig. 3 is a horizontal section taken on the plane of line 3—3 of Fig. 2, Fig. 4 is a detail view, partly in section, showing one of the merchandise supporting elements to be more fully described hereinafter, Fig. 5 is a detail view, illustrating one of the connections employed with my machine, and Fig. 40 6 is a fragmentary detail view, illustrating the construction of the platform supporting means.

Referring in detail to the drawings by numerals, 5 designates as an entirety, the 45 skeleton frame of the machine or rack, which is formed by four standards 6, connected at their upper terminals by the horizontal bars 7 and 8, and at their lower terminals by the horizontal frame bars 9 and 50 10. This frame may be made any desired size and of any suitable material.

A supporting rod 11 is connected at its terminals to the frame bars 8 centrally of their ends, and supports a plurality of T-shaped oscillating elements, designated as 55 entireties by the numeral 12, to which arti-

cles of merchandise may be connected. Each of the T-shaped members 12 comprises a head or cross bar 13 formed with a central transverse opening to receive the rod 11; and a depending centrally positioned arm 14. The arms 13 and 14 are formed with a plurality of apertures 15 providing a means for easily connecting articles of merchandise.

To the lower terminal of each of the arms 14 I connect a swing 16 in the form of a stirrup having side bars 17 and a central base bar 18. The side bars converge upwardly and are connected to the arms 14 by pivot pins 18'. These swings form convenient supports for articles of different natures which it is desired to display.

Directly under the rod 11, is arranged a supporting rod 20, held in position by means of brackets 21 secured to the base frame bars 10 centrally of their ends. This rod 20 supports a plurality of tilting or oscillating platforms 22, corresponding in number to the T-shaped elements 12. The connection 75 between the platform and the rod 20 may be made in any desired manner, such for instance, as by means of apertured ears 23, through which the rod 20 extends. These platforms are useful in displaying trays of goods, such trays may be placed thereon and removed therefrom easily and quickly.

The operating mechanism which actuates the T-shaped elements 12 and tilting platform 22, includes a crank shaft 24 journaled 90 between the rear frame standards 6 slightly below the corresponding frame bar 7. The crank shaft is provided with a plurality of cranks 25, the exact number depending upon the number of T-shaped members 12, and is 95 also equipped with a pulley 26 to be continually rotated by any suitable means, not shown. Bars 27 are loosely connected to the cranks 25 by hooks 28, best illustrated in Fig. 5. The lower terminals of these 100 arms or bars are connected pivotally to the rear ends of the tilting platforms 22 in any desired manner, such for instance, as by the pins 29 extending through rearwardly projecting lugs 30 into the bars 27. The rear 105 terminals of the cross bars 13 are connected to the dependent arms 27 by links 31 so that when the crank shaft 24 is rotated, the arm 13 and platform 22 will be oscillated in unit. The successive cranks 25 extend alternately in opposite direction so that when the mechanism comprising one unit of the ma-

chine is moving in one direction, the mechanism comprising the adjoining unit will be moving in the opposite direction.

From the foregoing description taken in connection with the accompanying drawings, it will be obvious that I have provided a very practical display rack or machine, which will keep articles of merchandise in continual motion, thereby more readily attracting the attention of passersby.

While I have shown and described the preferred embodiment of my invention, it will be understood that minor changes in construction, combination and arrangement of parts may be made without departing from the spirit and scope of the invention as claimed.

Having thus described my invention, I claim:

- 20 1. In a window display machine, a skeleton framework, a horizontal rod arranged at the top of said frame, an oscillating arm supported on said rod, an oscillating platform arranged at the bottom of the frame under said rod, a crank shaft, a bar dependent from the crank of said shaft and pivotally connected to one end of the platform, and a link connecting said bar to the oscillating rod.
- 25 2. In a window display device, a skeleton

frame, a horizontal rod arranged at the top of said frame, a plurality of oscillating arms mounted on said rod, a plurality of oscillating platforms arranged below said arms, a crank shaft, a plurality of bars dependent 35 from the crank shaft and pivotally connected at their lower ends to the oscillating platform, and a plurality of links connecting the oscillating arms with said bars.

3. In a window display device, a skeleton 40 frame, a plurality of oscillating T-shaped members arranged at the top of said frame, a plurality of oscillating platforms positioned within said frame below the oscillating arms, a crank shaft having a plurality 45 of cranks, a rod hooked at its upper end into engagement with each of said cranks, means pivotally connecting the lower terminals of the rods with the rear ends of said platforms, links connecting the rear terminals 50 of the T-shaped members with the rods, means whereby the crank shaft may be rotated to oscillate said arms and platforms, and swings connected to the central arms of the T-shaped members.

JOHN WILLIAM SCHAEFER.
